BLADE SHARPENER

Venry Aiello, Sr., Kenosha, Wis., assignor of one-third to Arthur K. Slack, Kenosha, Wis.

Application January 30, 1939, Serial No. 253,466

1 Claim. (Cl. 76—82.2)

This invention appertains to sharpeners, and more particularly to a novel universal device for sharpening bladed instruments, such as knives, shears, scissors, etc.

On of the primary objects of my invention is to provide a device in which the blade to be sharpened can be readily and quickly set to the proper and desired angle relative to the reciprocating sharpening member, whereby the blade can be accurately sharpened, even by a lay person.

Another salient object of my invention is to provide means whereby when the clamp is initially set for one blade of a pair of scissors or shears, or for one side of a knife relative to the sharpening member, such setting does not have to be changed for the other blade of the scissors or the other side of the knife, so that the sharpening can be quickly accomplished.

A further important object of my invention is the provision of a universal sharpening device for scissors and knives embodying means whereby a sharpening member can be reciprocated and accurately guided over the edge to be sharpened, with means whereby files of standard characters can be easily and firmly clamped on the reciprocating member.

A still further object of my invention is to provide a sharpening device of the above character, which will be durable and efficient in use, one that will be simple and easy to manufacture, and one which can be placed upon the market at a reasonable cost.

With these and other objects in view, the invention consists in the novel construction, arrangement, and formation of parts, as will be hereinafter more specifically described, claimed, and illustrated in the accompanying drawings, in which drawings:

Figure 1 is a side elevational view of my novel device, showing the same set up for sharpening a pair of scissors, parts of the view being shown broken away and in section to illustrate structural details.

Figure 2 is a top plan view of my improved device, showing the same adjusted and set for sharpening a pair of scissors, parts of this view being also shown broken away and in section.

Figure 3 is an enlarged, detail, sectional view taken on the line 3—3 of Figure 2, looking in the direction of the arrows, illustrating the novel clamp for the scissors.

Figure 4 is a sectional view taken on the line 4—4 of Figure 3, looking in the direction of the arrows, illustrating the clamp for the scissors.

Figure 5 is an enlarged, detail, transverse, sectional view through the operating handle, illustrating the single means employed for rigidly connecting a file and the guide member thereto.

Figure 6 is a side elevational view of my novel device set up and adjusted for sharpening a knife.

Figure 7 is an enlarged, detail, fragmentary, sectional view taken on the line 7—7 of Figure 6, looking in the direction of the arrows, illustrating the clamp for the knife.

Figure 8 is a detail, perspective view of a device which can be utilized for detachably connecting the frame of the sharpener to a table or other desired support.

Referring to the drawings in detail, wherein similar reference characters designate corresponding parts throughout the several views, the letter D generally indicates my novel universal sharpening device, which includes an open frame 10 of a substantially V-shape in plan.

The frame 10 can be cast in the desired form, or the frame can be constructed in any other preferred manner. Projecting forwardly from the frame 10 is a pair of spaced parallel arms 11, which are apertured for the reception of a transversely extending clamping and pivot bolt 12. The bolt adjacent its head is provided with an integral key or extension 13 for engaging in a groove or socket formed in the arms, whereby the bolt can be held against turning movement. As the socket or slot is formed in both of the arms 11, the bolt 12 can be placed in position from either side of the device. A winged nut 14 is threaded on the bolt for bringing the arms 11 toward and away from one another, as will be later set forth.

The frame 10 can be rigidly secured to a work bench, table, or other support 15, such as through the use of screws 16, which can extend through the frame and into the support. If preferred, a clamp 17 (shown in Figure 8) can be utilized in lieu of the screws 16. This clamp is of a U-shape in side elevation, and its upper leg can be secured to the frame by screws, rivets, or the like, and, as illustrated, the upper leg of the clamp and frame is provided with mating openings for the reception of such fastening elements. The lower leg of the clamp 17 carries an adjustable screw 18 for engaging the lower face of the table or other support with which the frame is associated.

The frame 10 is utilized for carrying and supporting a blade clamp 19 and a support 20 for the operating device 21.

The blade clamp 19 is particularly adapted for use when scissors or the like are being sharpened, and this blade clamp includes a pair of companion jaws 22 and 23. The jaws 22 and 23 are provided with companion, transversely alined, hinge barrels 24 and 25, which are mounted on the hinge bolt 12 between the arms 11 of the frame. Particular attention is invited to the fact that the jaw 22 has certain of its hinge barrels 24 disposed on the outside of the clamp and bolt the hinge barrels 25 of the jaw 23, and, thus, the arms 11 are adapted to engage and hold the outermost hinge barrels 24 of the jaw 22. This allows movement of the jaw 23, whereby blades can be positioned between the jaws 22 and 23 and then firmly clamped.

The inner face of the jaw 22 is provided with a scissor blade groove or seat 26, and this seat terminates short of one end of the jaw to provide a rest 27, which conforms to the curvature of the outer blunt edge of a scissor blade, whereby shifting movement of the scissor blade in the rest is prevented. Obviously, when the jaw 23 is brought into clamping position with the blade, the blade will be firmly held against movement.

Any desired means can be provided for adjusting the jaw 23 toward the jaw 22, and, as illustrated, the jaw 22 carries an arcuate threaded bolt 28, which extends through an opening in the jaw 23. Threaded upon the bolt 28 is a winged nut 29, which engages the jaw 23, and by threading up the nut on the bolt, the jaws can be held in their desired adjusted relation.

From the construction so far, it can be seen that both of the jaws 22 and 23 can be swung on the bolt 12 to a desired angular position, so that the blade being sharpened can be held at the proper angle, and that after such adjustment has been reached and the winged nut 14 has been tightened so as to move the arms 11 into clamping engagement with the jaw 22, the jaw 23 can be opened or closed for permitting the changing of the scissor blades therein.

The support 20 for the operating device 21 may, in the present instance, include a short threaded rod 30, which is adapted to be threaded into a socket 31 formed in the frame 10. The upper end of the rod is flattened and bifurcated to form spaced, parallel pivot ears 32, between which is received the forward end of a guide rod 33. This end of the guide rod has formed thereon an eye, and a pivot pin or bolt 34 extends through the eye and ears 32, whereby the guide rod is pivotally connected to the said rod. As the rod is free to turn in its socket, the guide rod 32 is mounted for universal movement.

The operating member 21 includes the guide rod 33 and an elongated guide sleeve 35 for receiving the rod. This guide sleeve 35 has formed on its outer end a shank 36, which is adapted to rest on one face of an arm 37 formed on the forward end of the operating handle 38. The operating handle is provided with a socket 39 in which is removably fitted the tang 40 of a file 41. This file is also adapted to engage the upper face of the arm 37 of the handle.

Detachably mounted upon the arm 37 of the handle is an open clamp loop 42, which is adapted to engage over the handle arm 37, the tang 40 of the file 41, and the shank 36 of the guide tube 35. This loop 42 carries an adjusting screw 43, and, obviously, by turning on the set screw 43, the guide sleeve of the tube 35 and file 41 can be firmly and rigidly secured to the handle. As the parts can be disconnected by merely turning

the screw 43, files of different fineness can be connected with the handle without difficulty.

In use of my improved device, the jaws 22 and 23 are loosened and the selected blade of a pair 5 of scissors S is placed on the seat 26, after which the winged nut 29 is tightened. The blade clamp 19 in its entirety is swung back and forth on the bolt 12 until the file rests correctly on the cutting edge of the blade, after which the winged nut 14 10 is firmly tightened. This will hold the clamp 19 against accidental swinging movement, and by grasping the handle 38, the file can be reciprocated back and forth and gradually swung over the scissor blade.

After the first scissor blade has been sharpened, the winged nut 29 is loosened, and the blade 15 of the scissors is removed from the clamp without changing the angle of the clamp. The other blade of the scissors, which has not been sharpened, is now placed in the seat 26, and the nut 20 is again tightened. The file is again reciprocated and brought across this blade of the scissors until it is sharpened.

In order to bring about the sharpening of knife 25 blades to the best advantage, I prefer to utilize 20 a special clamp, indicated by the reference character 50, and a special support 51 for the operating member 21.

The clamp 50 is somewhat along the line of 30 the clamp 19 in that the same includes movable jaws 52 and 53, having hinge barrels which are mounted on the pivot bolt 12, as the jaws of the clamp 19. In the clamp 50, the jaws extend a greater distance from the bolt 12, and the jaw 35 50 has a knife seat 54, which extends entirely across the jaw, and the jaw 52 is provided with a forwardly extending face 55, which is adapted 40 to extend into the seat 54. The jaws 52 and 53 are adjusted by means of a bolt 56 carried by the jaw 53, and which slidably extends through the jaw 52. A winged nut 57 is threaded on the bolt 56.

The support 51 is similar to the support 20, but the same extends a relatively great distance 45 above its frame 10 and above the clamp 50. Thus, the file extends downwardly at an angle toward the clamp 50 and the knife K to be sharpened. The knife blade is clamped between the jaws 52 and 53 by means of the nut 57 and the bolt 56, and the clamp is swung on its bolt 12 in such 50 a manner that the knife will be held at a proper angle for the file to rest thereon. Upon the tightening of the nut 14 of the bolt 12, the clamp 50 will be firmly held against movement, and 55 the blade of the knife can be quickly sharpened. After one edge of the knife has been sharpened, the nut 57 is loosened, and the position of the blade is reversed in the clamp and the nut 57 is again tightened. This side of the knife is then 60 sharpened without changing the initial setting of the clamp 50.

From the foregoing description, it can be seen that I have provided an exceptionally simple device for bringing about the efficient sharpening of bladed instruments, such as scissors, knives, etc.

Changes in details may be made without departing from the spirit or the scope of my invention, but what I claim as new is:

A sharpening device comprising, a frame, means 70 for securing the frame to a support, a supporting rod connected to the frame, a guide rod pivotally secured to the supporting rod, a guide tube reciprocally mounted on the guide rod, an operating handle connected with the tube, a sharpening

member connected with the tube and handle, a pair of spaced parallel arms on the frame, a transversely extending pivot bolt extending through and connecting said arms having a head on one end engaging the outer surface of one arm, and a nut threaded on the other end of the bolt for engaging the outer surface of the other arm, a blade clamp including a pair of companion jaws having hinge barrels rockably mounted on the bolt, whereby the jaws can be 10 adjusted relative to one another, and whereby the clamp as a unit can be adjusted on the bolt

to an angular adjusted position relative to the sharpening member, and means for holding the jaws in an adjusted position relative to one another, and hinge barrels for the innermost jaw being arranged beyond the hinge barrels of the outermost jaw for engagement by the inner faces of said arms, whereby said innermost jaw can be held against movement from a set position during adjustment of the outermost jaw relative to the innermost jaw.
